CLAIM

The ornamental design for a patient transfer stretcher,
as shown and described.

DESCRIPTION

FIG. 1 is a top plan view of a patient transfer stretcher
showing our new design;

FIG. 2 is a bottom plan view thereof, the bottom strap
being omitted for convenience of illustration;

FIG. 3 is a side elevational view thereof, the opposite
side elevational view being a mirror image of that
shown;

FIG. 4 is a front elevational view thereof; and,

FIG. 5 is a rear elevational view thereof.

FIG. 1

FIG. 2

FIG. 3

FIG. 4

FIG. 5
